ROOFING

Albert C. Fischer, Chicago, Ill.

Application April 10, 1935, Serial No. 15,538

4 Claims.

(CL 108—8)

This invention relates to waterproof surface covering strips, and particularly pertains to composition roofing elements formed into strips with ornamental designs imprinted upon the weather exposed surfaces.

Heretofore ornamental prepared asphalt roofing sheets or slabs have been manufactured from a foundation felt or fabric saturated and coated with bituminous compositions, and then surfaced with granular mineral material partially embedded in the coating as is conventional in roofing manufacture. Thereafter various designs may be effected by further embedding certain areas of the granular material into the coating to expose areas of asphalt coating to contrast with the color of the granular material. Or grooves of slight depth may first be depressed in the asphalt coating, and then the granular material is applied and partially embedded in those areas between the grooves. The depth of the groove is accentuated by reason of the granular surfacing. However, in carrying out these methods on ordinary asphalt saturated and coated sheets, the grooves or the granular material of the depressed areas cut into and weaken the foundation felt. Obviously this weakens the strips which themselves are relatively thin and flexible rather than being thick and board-like in character.

The present invention aims to provide ornamental roofing which is made relatively thick and board-like, whereby depressions or ridges may be formed on the exposed face to provide ornamental and artistic designs irrespective of the granular surfacing and without weakening the strips. The roofing is preferably composed of a homogeneous mixture molded into sheets of substantial thickness.

For a full and more detailed understanding of the invention reference is made to the accompanying drawing, in which:

Figures 1 and 2 are perspective views of one embodiment of the invention;

Figures 3 and 4 are perspective views of a modified form of the invention;

Figure 5 is a perspective view of another embodiment of the invention;

Figure 6 is a top plan view of Figure 1; and

Figures 7 and 8 are perspective views of still further embodiments.

Referring to the drawing, numeral 2 designates a roofing sheet which is composed of a mass of bituminous material, such as asphalt, and a filling thoroughly intermixed and molded into form. A suitable filling may comprise com-

minuted fibrous and/or mineral material. The fibres of the fibrous filler are of sufficient length to bond the bituminous material into a cohesive mass. The mineral filler gives body to the mass and a greater degree of density. If desired, the filling content may comprise as much as seventy-five (75) per cent of the mixture, but preferably it is combined with the bituminous material in about equal proportions. The proportion of mineral to the fibrous filler may vary to any extent, dependent upon the desired degree of density in the resulting mass.

To prepare a suitable mixture, the bituminous and filling components are mixed into a warm plastic mass in any conventional steam heated mixer or the like until they have been commingled into a homogeneous mass. Thereafter the warm, plastic mass is fed into a steam jacketed extrusion device to be formed into a continuous densely compressed strip, which may subsequently be subdivided into suitable lengths. While the strip is warm, and preferably before being subdivided, one face is imprinted with an ornamental design.

One design (Figures 1 and 2) may be in the form of complementary, concave depressions 3 and convex ridges 4 alternately disposed and extending transversely of the strip. Preferably the strip is of tapered configuration with the thicker portion 5 comprising the weather edge of the strip, and the transverse depressions and ridges formed only on the weather exposed face. If it is desired to cover the weather exposed face of the strip with granular material, one marginal edge 6 is preferably left uncoated in order that it may contact with the under marginal surface of an adjacent strip when overlapped in courses. In imprinting the depressions, some of the bituminous material will be caused to flow or roll over the edge of the strip in the form of artistic waves 7. These waves may vary in extent, terminating short of the reverse side of the strip or, if desired, extending flush with the reverse side of the strip as shown at 8 in Figure 3. Also they may be formed on the edges of the ridges 45 as at 9 in Figure 4 as well as on the edges of the depressions.

The embodiment in Figure 5 shows a different design formed on the weather exposed side of the roofing or siding element. The strip has one edge thickened and a series of raised portions 10 are set off at intervals by depressions 11. In forming the depressions and raised portions a portion of the material is squeezed to project beyond the base edge of the strip in order to pro-

vide a continuous marginal lip 12 and 13. Numeral 12 designates that portion of the marginal lip which projects from the raised portion, and 13 designates that portion which projects from the depressed portions 11.

In the embodiment in Figure 7 the same general structure results in the strip as in that embodiment in Figure 5, but the raised portions 10¹ are of different contour, being somewhat convex 10 on the outer surface. Formation of the recesses 11¹ and the raised portion 10¹ squeeze the material to provide a continuous lip, including the portions 12¹ which project from the raised portions and 13¹ which project from the recessed portions 11¹. The raised portions in any of the embodiments may be merely coated with a waterproofing coating or may have granular material partially embedded in a waterproofing coating or in the composition material from which 20 the roofing or siding sheet is made.

In Figure 8 a siding or roofing sheet of the same composition as the other embodiments is shown. This, however, is molded or embossed to effect a different design. Sheet 14 is provided 25 with a series of terraced or stepped portions 15 extending longitudinally of the strip 14. These terraced or stepped portions 15 may be further set off into raised portions 17 by providing a series of cross grooves or lines 16 if the roofing 30 or siding is provided with granular surfacing material. The lines 16 may be effected by leaving these portions uncovered, thereby causing the composition material to be exposed at these areas to contrast with the other portions which 35 are covered with the granular material. As a result the roofing or siding effects certain novel designs by virtue of the stepped portion and also the exposed surface is made to simulate individual shingles by the transverse divisions 16. 40 The top edge of the shingle is preferably of reduced thickness in order that it may overlap, and a series of these shingles or strips may be laid in overlapping courses to cover a roofing or siding structure.

45 While I have shown several preferred embodiments of my invention, and detailed descriptions thereof, it will be understood that the invention is not limited thereby but that various changes

may be made therein without departing from the spirit of the invention.

I claim:

1. A covering strip comprising a homogeneous mass of adherent plastic material having a plane undersurface, a series of elongated raised portions and depressions formed on the weather exposed face to provide an ornamental design, some of said depressions being extended to merge with the butt edge of the strip, and a marginal projection extending along the butt edge of the strip and conforming to the surface contour of the raised portions and those depressions which merge with the butt edge of the strip. 5

2. A covering strip comprising a homogeneous mass of adherent plastic material having a plane undersurface, a series of elongated raised portions formed on the weather exposed face to provide an ornamental design, all of said raised portions and depressions being extended to merge 15 with the butt edge of the strip, and a marginal projection extending along the butt edge of the strip and conforming to the surface contour of the raised portions and depressions. 20

3. A covering strip comprising a homogeneous mass of adherent plastic material having a plane undersurface, a series of elongated raised portions and depressions formed on the weather exposed face to provide an ornamental design, one of said depressions being extended to merge with 25 the butt edge of the strip, and a marginal projection extending along the butt edge of the strip and conforming to the surface contour of the strip adjacent its butt edge. 30

4. A covering strip comprising a homogeneous mass of adherent plastic material having a plane undersurface, a series of elongated raised portions and depressions formed on the weather exposed face to provide an ornamental design, some of said depressions being extended to merge with 40 the butt edge of the strip, a marginal projection extending along the butt edge of the strip and conforming to the surface contour of the raised portions and those depressions which merge with the butt edge of the strip, and granular coating material applied to the raised portions. 45

ALBERT C. FISCHER.
